UNITED STATES PATENT OFFICE

160,402

BICYCLE

Harry W. Kranz, Lakewood, Ohio, assignor to The
Cleveland Welding Company, Cleveland, Ohio,
a corporation of Ohio

Application January 3, 1950, Serial No. 6,971

Term of patent 7 years

(Cl. D90—8)

To all whom it may concern:

Be it known that I, Harry W. Kranz, a citizen of the United States and resident of Lakewood, county of Cuyahoga, and State of Ohio, have invented a new, original, and ornamental Design for a Bicycle, of which the following is a specification, reference being had to the accompanying drawing, forming a part thereof.

In said annexed drawing:

Fig. 1 is a side elevational view of a bicycle showing my new design;

Fig. 2 is a top plan view thereof;

Fig. 3 is a front elevational view; and

Figs. 4 and 5 are enlarged perspective views of the rear and front scuff bars respectively removed from the bicycle.

The dominant features of my design reside in that portion shown in full lines in the drawing.

I claim:

The ornamental design for a bicycle, as shown and described.

HARRY W. KRANZ.
